ROTARY PUMP OR MOTOR

Ambrose White, Kentwood, La.

Application June 20, 1952, Serial No. 294,587

11 Claims. (Cl. 103—125)

1

The invention relates to improvements in converting gaseous and hydraulic pressure to mechanical energy, and to convert mechanical energy to gaseous and hydraulic pressure in which a piston or vane with ports and wiper bars bolted to a rotor which has pressure chambers, rings, shaft, bearings, casing, ports, and suspended plate valves, working in conjunction with a rotating abutment equipped with casing, shaft, bearings, and an adapter, connected or timed together by gears, revolves in an endless circle; and the objects of the improvements are, first, to eliminate all reciprocating motion; second, to effect a circular power stroke; third, to create one circular power stroke for each revolution; fourth, to obtain a longer power stroke in a given space; fifth, to provide adequate rotor, rotating abutment and casing space for water cooling of all parts exposed to high temperatures; sixth, to create one single machine that will convert gaseous and hydraulic energy to mechanical energy or mechanical energy to a gaseous or hydraulic pressure.

One form of the invention is illustrated in the accompanying drawing, in which:

Figure 1 is a vertical longitudinal half section of the entire machine;

Figure 2, a right vertical half section, illustrating the principal moving parts;

Figure 3, a cut-away section of the rotor 1, with the piston 5 removed, clearly illustrating the ports 15 and 16, and their connections to the pressure chambers 6 and 7, respectively;

Figure 4, a detailed view of the piston 5;

Figure 5, a sketch of the rotating abutment 2, illustrating the adapter which permits the passage of the piston 5, between the rotor 1, and rotating abutment 2; and,

Figure 6, an elevational view of the non-rotating plate valve 30, with its suspension and adjustment bar 31, and valve adjustment plate 32.

Figures 7 to 16, inclusive, illustrate a modified form of the invention providing a plurality of rotors, each with a piston arranged within a single casing in cooperative relation with a single, central rotating abutment and having a jacketed construction providing a cooling and sealing system.

Figure 7 is a vertical longitudinal section of the modified form of the invention, taken on the line 7—7 of Figure 8.

Figure 8 is a central transverse section taken on the line 8—8 of Figure 7.

Figure 9 is a partial transverse section taken on the line 9—9 of Figure 7.

2

Figure 10 is an additional partial transverse section taken on the line 10—10 of Figure 7.

Figure 11 is a further partial transverse section taken on the line 11—11 of Figure 7.

Figure 12 is a side perspective view, partially sectioned showing a rotor of the modified invention.

Figure 13 is an end perspective view of the rotary abutment of this embodiment.

Figure 14 is an end perspective view of the piston used in the modified invention.

Figure 15 is a side perspective view of one end closure member for the housing or casing.

Figure 16 is a similar side perspective view of the other end closure member.

In Figures 1 and 2, the rotor 1, and its detachably secured piston 5, are suspended in the completely enclosed casing 18, by bearings 12, 12, and shaft 3, which permit the rotor 1, with its eight sealing rings 17, to revolve freely in a clockwise or counter-clockwise direction. Likewise, the rotating abutment 2 can revolve in either direction and is completely enclosed with a close moving fit in casing 19, suspended by a countershaft 4, with bearings 13, 13, and connected in perfect time to the rotor 1, by any suitable gears 9 and 8, which are made fast to respective ends of shafts 4 and 3, with keys 10 and 11. The casing 19 is bolted to the casing 18, and provided with a suitable sealing gasket 29, which has sufficient thickness so that a leakproof bridging contact is assured between the abutment casing 19 and the rotor casing 18. As shown in Figures 1 and 5, the rotating abutment 2 has even or identically tapered ends so as to provide a single line of tangency with the rotor 1. Further, the circular diameter of the rotating abutment 2 is equal to the smallest circular diameter of the rotor 1, at their point of tangency, which minimizes sliding or friction between the two parts referred to, while in motion.

In Figure 1, end chambers 6 and 7, of the rotor 1, have been designed in such a way that all in-coming or out-going gas or liquid cannot cause or effect a thrust on the entire rotor; and that rings 17, between the rotor 1, and its casing 18, are provided to hold the said gas or liquid in its directed route. Thrust set up by partial ring leakage between rotor 1 and casing 18 is prevented by an equalizing line or groove 14, which is cut along the rotor shaft 3, and equalizes such pressure on both ends of the rotor 1. As shown in Figure 1, the shaft groove 14 interconnects the opposite end spaces between the casing 18 and the rotor 1, thus trans-

ferring any excess leakage pressure in one end space to the other. In Figures 1 and 6, the pressure chambers 6 and 7 may be further provided with two identical suspended stationary plate valves 30, 30 (one in each chamber) in cut-off relation to respectively adjacent ends of ports 15 and 16 and connected by means of swivel 33, loosely fitted to a suspension and adjustment bar 31, which is screwed through a valve adjustment plate 32, that is bolted to the outside of the rotor casing 18. The stationary plate valves 30, 30 are most accurately adjusted by the suspension and adjustment bars 31, 31, in pressure chambers 6 and 7, in such a position that the port holes 15 and 16 will be entirely closed when the revolving piston 5, bolted to the rotor 1, reaches its point of interengagement with the rotating abutment 2, and that they will be open after the revolving piston 5 passes out of interengagement with the rotating abutment 2.

The adjustable stationary plate valves 30 contribute to the efficiency and flexibility of operation. When the revolving piston 5 is passing through its period of interengagement with the rotating abutment 2 a condition of opening arises which permits pressure fluid from the admission port hole 15 to pass over the outer end of piston 5 and to the exhaust port hole 16 without performing any useful work. Proper angular setting of the plate valves 30 prevents this loss. These plate valves 30 may also be adjusted to vary "cut off" so that the fluid within the work chamber can expand more fully. In starting, the plate valves 30, 30 can be manually shifted from normal position if necessary in order to pass pressure fluid through a closed port hole into work chamber 34.

When a gas or hydraulic pressure is built up in pressure chamber 6, Figure 1, through the opening 20, in casing 18, or by any other means, and the rotor 1, with the fixedly secured piston 5, is moved counterclockwise, Figure 2, to a point where the piston 5 has cleared its area of interengagement with the rotating abutment 2, the port hole 15 will have passed from behind the stationary plate valve 30, permitting the pressure substance to flow through the block of rotor 1, piston 5, and build up a pressure within the work chamber or cylinder space 34, between the piston 5, and the rotating abutment 2, which will force the piston 5, and the rotor 1, to continue its same rotation. At the same time port hole 16 will have passed from behind its stationary plate valve 30, in pressure chamber 7, permitting any pressure trapped between the opposite side of the piston 5, and the rotating abutment 2, to exhaust or escape freely through the piston 5, rotor block 1, on to the pressure chamber 7, and out through the opening 21, in casing 18. The revolving inertia set up in the rotor 1, piston 5, and rotating abutment 2, at the end of the circular power stroke where port hole 15 passes behind the stationary plate valve 30, will, without the benefit of a flywheel, cause the piston 5 to pass through its interengagement area with the rotating abutment 2, and, therefore, start a new cycle.

If at any time, in the process of converting gaseous and hydraulic pressure to a mechanical energy, it is desirable to reverse the rotation of the mechanical converter, the fluid pressure in pressure chamber 6 is relieved and a pressure is built up in pressure chamber 7, whereas, the same

chain of reaction will apply as described in the preceding paragraph.

In Figures 1 and 2, when the shaft 3 is turned in the bearings 12, 12, rotating the rotor 1, and piston 5, in a counterclockwise rotation and through the gear 8, which is made fast to the shaft 3, rotates gear 9, which is made fast to shaft 4, in the bearings 13, 13, and simultaneously turns the rotating abutment 2, in a clockwise rotation in which the arcuate adapter recess 2a in the rotating abutment 2 is in perfect time with the piston 5, which is bolted to the rotor 1. The piston 5, moving away from the rotating obstruction 2, creates a decreased pressure in the work chamber 34. This decreased pressure begins in work chamber 34, at the point where the piston 5 leaves its interengagement with the rotating abutment 2, and, whereas, the port hole 15 passes from behind the plate valve 30, in pressure chamber 6, thereby, causing a decreased pressure in pressure chamber 6, which will readily attract the flow of gas or liquid through the opening 20, in casing 18. While at the same time, on the opposite side of the piston 5, which is moving in a circular direction toward the rotating abutment 2, a pressure is being built up in work chamber 34, beginning at the point where the piston 5 leaves its interengagement with the rotating abutment 2, and, whereas, the port hole 16 passes from behind the stationary plate valve 30, in chamber 7 permitting the gas or liquid to flow into pressure chamber 7, and out through the opening 21, in casing 18.

If at any time it is desired to change the direction of the gas or liquid flowing through the mechanical converter, it can be accomplished by reversing the rotation of shaft 3, whereas, the same reaction as described in the preceding paragraph will occur, only, in the reverse order.

The basic aspects of the rotary pump or motor invention described in detail and disclosed in Figs. 1 to 6, inclusive, are carried forward in the modified embodiment of Figs. 7 to 16, inclusive, to provide for a plurality of rotors spaced symmetrically about a single or common rotating abutment for greater and more uniform power output. This modified embodiment provides also for jacketing of the rotors, rotating abutment and rotor pistons for cooling, sealing and lubricating, and for including pump means to circulate fluid in the jacketed parts.

Since this modified form of the invention incorporates much that is common to the principal embodiment, only the features of improvement will be described with particularity. Figs. 7 and 8 taken together show the manner in which a plurality of rotors 41 (in this case three) are disposed symmetrically about a common rotating abutment 42 for individual cooperation therewith. The conical-ended abutment 42 is formed with an arcuate peripheral recess 42a. As will be explained in further detail, each of the rotors 41 is jacketed and has jacketed housing means. The three rotors 41 are maintained in spaced, parallel relation to each other and to the rotating abutment 42 in the manner shown in Fig. 8.

Each of the rotors 41 is mounted on a power shaft 43 and has a spur gear 48 secured on an outer end by a key 51. Bearing formations 52 are provided at the opposite ends of the shafts 43.

The central rotating abutment 42 is mounted for rotation on and with countershaft 44 supported at spaced end portions by bearing forma-

tions 53 as shown in Fig. 7. The rotor shafts 43 are equidistant from each other and the central countershaft 44. An appropriately sized spur gear 49 is secured by a key 50 to the projecting end of the shaft 44 for interengagement with the gears 48 of the several rotors 41.

The rotors 41, one of which is shown in detail in Fig. 12, and in association with casing or housing means including cylindrical units 58 with abutment openings 59, and the rotating abutment 42 in Fig. 8, are of the same general construction as disclosed in the principal embodiment. Each is formed to provide at opposite ends annular pressure chambers 46 and 47 supplied by fluid openings 60 and 61, respectively, in each rotor casing unit 58. Sealing rings 57 are mounted on opposite ends of the rotors 41 at each side of the peripheral portions defining the pressure chambers 46 and 47. Each shaft 43 is formed with a longitudinal pressure equalizing groove 54.

A rotor port 55 extends from the pressure chamber 47 longitudinally of the rotor 41 to the central reduced portion thereof, and rotor port 56 extends similarly in a longitudinal direction from the opposite pressure chamber 46. Jacketing space is provided for the rotor ports 55 and 56, which ports discharge through the outwardly flared extensions formed in the piston 45 in the manner previously described.

The common rotating abutment 42 and the plurality of surrounding rotors 41 with their cylindrical casing units or housings 58 are maintained in the assembled relation shown in Fig. 8 by means of three generally V-shaped side closure elements 62 secured by bolts 63 as shown best in Figs. 7, 8 and 11. The inner end portions of the elements 62 are of a length to close the spaces left between the sides of cylindrical units 58, and are shaped complementally with respect to the adjacent periphery of the rotating abutment 42. Central end closure pieces 64 and 65 of spider shape are fitted over opposite end portions of the abutment countershaft 44 as shown by Fig. 7. Figs. 15 and 16, which separately show the closure pieces 64 and 65, indicate shouldered end portions 67 and 68, respectively, for interfitting with and supporting the extending ends of the side closure elements 62. These pieces 64 and 65, which serve to complete the enclosure of the rotating abutment 42, are secured by bolts 66 to the casing units 58. As shown best in Figs. 7 and 11, the end openings of the respective rotor ports 55 and 56 are regulated by adjustable valve plates 70, each carried on a valve adjustment bar 71 threaded into a valve adjustment plate 72 on the outside of the respective housing portion 58. A swivel connection 73 between the inner end of the bar 71 and the outer portion of the valve plate 70 permits accommodation to adjusting movement.

It will be understood that each of the rotors 41 functions as before in that inlet of working fluid to and outlet of working fluid from the pressure chambers 46 and 47 is through the fluid openings 60 and 61. This fluid flow is controlled by cyclic interengagement and lack of interengagement between the piston member 45 of the rotor 41 and the recess 42a of the rotating abutment 42, as modified by the settings of the valve adjustment plates 70 over the ends of the ports 55 and 56. The piston member 45 sweeps the annular work space 40.

The details of the jacketing construction for the rotors 41 and the rotating abutment 42 as

shown in Figs. 7, 8, 9, and 10 can best be explained by reference to the passage of the cooling and sealing fluid therethrough. This fluid may also provide some lubrication. Such fluid enters a rotor casing or housing 58 at entry connection 74 and leaves it at exit connection 75 as indicated in Fig. 7.

Before proceeding, it is to be observed that the jacket spaces on opposite sides of the pressure chamber 46 include integral centrifugal pumps 76 and 77 shown respectively in detail in Figs. 9 and 10. Each of these pumps (76 and 77) includes appropriately shaped and disposed vanes 78 or 79. The random curved arrows in these two figures indicate the direction of flow of the cooling medium when the shaft 43 of the rotor 41 is turning clockwise. In Fig. 9, the cooling fluid is flowing from the peripheral portion of the pump 76 to the central portion, and in Fig. 10 the fluid is flowing in the opposite direction, that is, from the central portion outwardly to the peripheral jacketing portion.

It is to be noted that in Fig. 7 another set of identical centrifugal pumps are located in the end spaces opposite the sides of the companion pressure chamber 47. The vanes in the space nearer the center of the rotor 41 are identical in contour and arrangement to those of pump 76, and those in the more remote space are identical in contour and arrangement to those found in the pump 77. Additional showing of these two identical pumps and further description of their duplicating details is believed unnecessary.

The arrangement of the two sets of centrifugal pumps (76 and 77) is such that when continuous combustion is set up in pressure chamber 47, the fluid cooling medium will be drawn in through the opening or entry connection 74, around the annular jacket space b, to the top and down through the vanes 78 of the centrifugal pump 76 (Fig. 9). When this fluid reaches the inner annular jacket space c adjacent the shaft 43, it will be picked up by the centrifugal pump 77, and forced outwardly into the intermediate and annular inwardly directed rotor jacket space d, before reaching the separate, annular jacket space e. The cooling and sealing fluid leaves the annular jacket space e at the top, moves into the adjacent end of the space ra completely jacketing the rotating abutment 42, and leaves at the opposite end. At this point, the cooling and sealing medium enters a jacket space f, companion in shape and arrangement to space e, whence it flows around to the bottom and continues through the pump 76 communicating therewith, supplying the inwardly directed annular rotor space g on the way. On leaving this pump 76, the said fluid passes into the jacket space h and moves therethrough to the more outer centrifugal pump 77 discharging to an additional separate, annular jacket space i, and passes therearound to the fluid exit connection 75 at the bottom of the rotor casing 58.

Figs. 7, 8 and 10 illustrate the manner in which the port portions of the rotors 41 and their pistons 45 are cooled by fluid circulating in the jacket spaces g or d, through an interconnecting space k and a communicating space m extending radially within each rotor 41 and centrally of its piston 45.

Cooling fluid intercommunication between the several rotor casings 58 and the jacket spaces e and f is obtained through suitable porting of the central end closure pieces 64 and 65, as shown for piece 65 in Fig. 10.

There are a number of advantages in this system of forced circulation for the fluid cooling or other heat exchange medium. It will insure sealing of all minute openings between the relatively movable parts, and at the same time, provide a degree of lubrication. Regardless of the direction in which the rotors 41 are turning as determined by combustion or pressure fluid in either of the pressure chambers 46 or 47, the cooling fluid will be admitted at the exhaust end and discharged at the combustion end of the machine. In this manner the water or other fluid will pick up its latent heat from the expanded gases of the exhaust and transfer it back through the machine to the combustion end, thus preventing stress and strain resulting from successive expansion and contraction of the metals cooled.

If small leakage of water reaches the area of burning gases, it may be used beneficially in accordance with the practice of injecting water into internal combustion engines for added efficiency.

The present application is a continuation in part of my co-pending application Serial Number 75,021, filed February 7, 1949, now abandoned.

I am aware that prior to my invention, other types of machines have been made that will convert a gaseous and hydraulic pressure to a mechanical energy, and still others which will convert mechanical energy to a gaseous or hydraulic pressure, using shafts, keys, gears, and various types of rotors, etc. Therefore, I do not claim the aforementioned mechanical parts broadly; but having thus described my invention, what I claim as novel and desire to secure by Letters Patent of the United States is:

1. A rotary pump or motor comprising a rotor shaft; an elongated cylindrical rotor carried on and rotatable with said rotor shaft, said rotor being formed with an annular fluid space adjacent each end and extending inwardly from the peripheral surface of the rotor, an intermediate annular cylinder space also extending inwardly from said peripheral surface, and a pair of closely spaced longitudinally and oppositely extending port passages running from the bottom surface of said cylinder space to respectively adjacent fluid spaces; a countershaft; a rotating abutment of cylindrical cross section and having a diameter equal to that of the bottom surface of the rotor cylinder space, carried on and rotatable with said countershaft in line contact relation with said bottom surface, said rotating abutment being formed with an axially extending, symmetrical peripheral recess of arcuate shape, the innermost part of which is spaced from the bottom surface of the rotor cylinder space a distance equal to the depth of said cylinder space; a piston member fixed to said rotor within the cylinder space and over said port passages, said piston member being formed with an outer configuration complementally engaging and spanning the recess of the rotating abutment and having circumferentially spaced nozzle openings in said outer configuration leading respectively to said port passages; and a sealed casing fitting closely over and conforming to the sides and ends of said rotor and rotating abutment, said casing having openings communicating separately with each of the annular fluid spaces of the rotor.

2. A rotary pump or motor comprising a rotor shaft; an elongated cylindrical rotor carried on and rotatable with said rotor shaft, said rotor

being formed with an annular fluid space adjacent each end and extending inwardly from the peripheral surface of the rotor, an intermediate annular cylinder space also extending inwardly from said peripheral surface, and a pair of closely spaced longitudinally and oppositely extending port passages running from the bottom surface of said cylinder space to respectively adjacent fluid spaces; a countershaft; a rotating abutment of cylindrical cross section and having a diameter equal to that of the bottom surface of the rotor cylinder space, carried on and rotatable with said countershaft in line contact relation with said bottom surface, said rotating abutment being formed with an axially extending, symmetrical peripheral recess of arcuate shape, the innermost part of which is spaced from the bottom surface of the rotor cylinder space a distance equal to the depth of said cylinder space; a piston member fixed to said rotor within the cylinder space and over said port passages, said piston member being formed with an outer configuration complementally engaging and spanning the recess of the rotating abutment and having a pair of circumferentially spaced nozzle openings in said outer configuration leading respectively to said port passages and flaring away from each other as smoothly curved continuations of the adjacent ends of said port passages; and a sealed casing fitting closely over and conforming to the sides and ends of said rotor and rotating abutment, said casing having openings communicating separately with each of the annular fluid spaces of the rotor.

3. The combination of claim 1 in which the ends of the rotating abutment are conical and the cross section of the annular cylinder space of the rotor is formed for complemental engagement with the portion of the rotating abutment received therein.

4. The combination of claim 1 in which the rotor shaft is formed with a grooved passage connecting the spaces between the ends of said rotor and the casing.

5. A rotary pump or motor comprising a rotor shaft; an elongated cylindrical rotor carried on and rotatable with said rotor shaft, said rotor being formed with an annular fluid space adjacent each end and extending inwardly from the peripheral surface of the rotor, an intermediate annular cylinder space also extending inwardly from said peripheral surface, and a pair of closely spaced longitudinally and oppositely extending port passages running from the bottom surface of said cylinder space to respectively adjacent sides of said fluid spaces; a countershaft; a rotating abutment of cylindrical cross section and having a diameter equal to that of the bottom surface of the rotor cylinder space, carried on and rotatable with said countershaft in line contact relation with said bottom surface, said rotating abutment being formed with an axially extending, symmetrical peripheral recess of arcuate shape, the innermost part of which is spaced from the bottom surface of the rotor cylinder space a distance equal to the depth of said cylinder space; a piston member fixed to said rotor within the cylinder space and over said port passages, said piston member being formed with an outer configuration complementally engaging and spanning the recess of the rotating abutment and having circumferentially spaced nozzle openings in said outer configuration leading respectively to said port passages; and a sealed casing fitting closely over and conform-

ing completely to the sides and ends of said rotor and rotating abutment, said casing having openings communicating separately with each of the annular fluid spaces of the rotor; and a plate valve segment adjustably supported from the casing and positioned in cooperative relation to the end of the respective longitudinal port passage in each annular fluid space of the rotor.

6. A rotary pump or motor comprising a rotor shaft; an elongated cylindrical rotor carried on and rotatable with said rotor shaft, said rotor being formed with an annular fluid space adjacent each end and extending inwardly from the peripheral surface of the rotor, an intermediate annular cylinder space of symmetrical trapezoidal cross section also extending inwardly from said peripheral surface, and a pair of closely spaced longitudinally and oppositely extending port passages running from the inner bottom surface of said cylinder space to respectively adjacent sides of said fluid spaces; a countershaft; a cylindrical rotating abutment with conical ends having its outer portion complementary to and coextensive with the cross-section of the rotor cylinder space, and carried on and rotatable with said countershaft, said rotating abutment being also formed with an axially extending, symmetrical peripheral recess of arcuate shape, the innermost part of which is spaced from the bottom surface of the rotor cylinder space a distance equal to the depth of said cylinder space; a piston member fixed to said rotor within the cylinder space and over said port passages, said piston member being formed with an outer configuration complementary engaging and spanning the recess of the rotating abutment and having circumferentially spaced nozzle openings in said outer configuration leading respectively to said port passages and flaring away from each other as smoothly curved continuations of the adjacent ends of said port passages; a sealed casing fitting closely over and conforming to the sides and ends of said rotor and rotating abutment, said casing being provided with an opening communicating with each of the annular fluid spaces of the rotor, and said rotor shaft being grooved to provide a passage connecting the spaces between the ends of said rotor and the casing; and a plate valve segment adjustably supported from the casing and positioned in cooperative relation to the end of the respective longitudinal port passage in each annular fluid space of the rotor.

7. The combination of claim 1 in which the cylindrical rotor is formed to provide cooling fluid passages on opposite ends of each annular fluid space and in the portion thereof inwardly adjacent the intermediate annular cylinder space, and all said fluid passages are intercommunicating.

8. The combination of claim 7 in which the casing is formed with annular jacket spaces surrounding the cylindrical rotor, and in which the piston member is formed with a fluid passage connected with the said adjacent fluid passages of the cylindrical rotor.

9. A rotary pump or motor comprising a plurality of spaced, parallel rotor shafts equidistant from each other; an elongated cylindrical rotor carried on and rotatable with each of said

5 rotor shafts, each of said rotors being formed with an annular fluid space adjacent each end extending inwardly from the peripheral surface of the rotor, an intermediate annular cylinder space also extending inwardly from said peripheral surface, and a pair of closely spaced longitudinally and oppositely extending port passages running from the bottom surface of said cylinder space to respectively adjacent fluid spaces; a countershaft extending in spaced parallel relation to and equidistant from each of said rotor shafts; a rotating abutment of cylindrical cross section and having a diameter equal to that of the bottom surface of each rotor cylinder space, carried on and rotatable with said countershaft in line contact relation with each of said bottom surfaces, said rotating abutment being formed with an axially extending symmetrical peripheral recess of arcuate shape, the innermost part of which is spaced from the bottom surface of each rotor cylinder space a distance equal to the depth of said cylinder space; a piston member fixed to each of said rotors within its cylinder space and over the port passages thereof, said piston members each being formed with an outer configuration complementary engaging and spanning the recess of the rotating abutment in its turn and having circumferentially spaced nozzle openings in said outer configuration leading respectively to the port passages thereof; and a casing fitting closely over and conforming to the sides and ends of each of said rotors and rotating abutment, said casings each having an opening receiving an arcuate segment of the rotating abutment, and fluid inlet and outlet openings communicating respectively with the annular fluid spaces of the rotors.

10. The combination of claim 9 in which each 40 rotor is formed to provide intercommunicating cooling fluid passages on opposite ends of each annular fluid space, the rotating abutment is formed with an annular fluid passage, each casing is formed to provide fluid passages extending 45 annularly about its rotor and in communication with said rotor fluid passages, and the opposite ends of the annular fluid passage of the rotating abutment communicate with said casing fluid passages.

11. The combination of claim 9 in which each 50 rotor is formed to provide with its casing annular cooling fluid passages extending radially on opposite ends of each annular fluid space, each pair of said annular passages being connected by a passage adjacent the rotor shaft, in which a centrally discharging centrifugal pump is formed in the outer annular passage and a peripherally discharging centrifugal pump is formed in the inner annular passage of one pair, and a centrally discharging centrifugal pump and a peripherally discharging centrifugal pump are formed in converse relation in the other pair, and each casing is formed with annular cooling fluid passages interconnected through the fluid abutment to conduct cooling fluid from one end of the rotor to the other.

AMBROSE WHITE.
